UNITED STATES PATENT OFFICE.

JOSEPH G. ALLMON, OF OAKLAND, CALIFORNIA.

WRENCH.

1,291,633.

Specification of Letters Patent. Patented Jan. 14, 1919.

Application filed February 11, 1918. Serial No. 216,490.

To all whom it may concern:

Be it known that I, JOSEPH G. ALLMON, a citizen of the United States, residing at Oakland, in the county of Alameda and 5 State of California, have invented certain new and useful Improvements in Wrenches, of which the following is a specification.

This invention relates to improvements in wrenches and more particularly to an 10 article of this character which is adapted for use in connection with pipe flanges. It will be understood that flanges for which my wrench is adapted, are provided with bolt holes and are in screw-threaded engagement with the supporting pipe.

The principal object of my invention is to provide a tool by which pipe flanges may be readily screwed to the supporting pipe or removed therefrom. A further object 20 of my invention is to so arrange the various parts that a pin which is inserted in one of the bolt holes of the flange is not subject to a twisting action, and a still further object is to provide a wrench which is strong 25 in construction, easily applied to the work, and which gives the maximum strength for a given weight.

With these and other objects in view, the 30 invention consists of certain novel features of construction, combinations and arrangements of parts hereinafter described and more specifically pointed out in the appended claims; it being understood that changes 35 of construction within the scope of the claims may be resorted to without departing from the spirit of the invention or sacrificing any of the advantages thereof.

Reference being had to the drawing 40 forming a part of this specification,

Figure 1, is a view in perspective of my improved wrench.

Fig. 2, is a view in plan of the same showing also the manner in which it is applied 45 on a pipe flange.

Fig. 3, is a view in side elevation.

Referring to the corresponding parts by the same numerals, the wrench comprises a flat head denoted in general by 1, a handle 50 2 and an intermediate polygonal portion 3. Adjacent the forward end of the head 1 are provided pins 4 and 5, extending outwardly from opposite faces of this head and of such diameters that they fit closely in the 55 bolt holes of different sized standard flanges.

This head is substantially wedge-shaped

in contour with the pins 4 and 5 near the narrow end and the wide end connecting to the intermediate portion 3. On the sides of the wide end of the head are lugs 6 and 7 which extend from opposite faces of the head 1 and are provided on their outer ends with inwardly extending lips 8.

The distance between the face of the head and the underside of the lips 8 is substantially equal to the thickness of the flange, the bolt-holes of which correspond in diameter to that of the respective pins 5 or 4.

The upstanding portion 9 of each of these lugs is preferably arranged with its inner 70 face on an angle which is tangent to a circle having its center in the axis of pin 4 or 5. As here shown, these lugs are symmetrically disposed on either side of the longitudinal median line of the tool, which 75 makes it necessary that the smaller pin be set back of the larger, as the flanges having the smaller diameter have the smaller bolt-holes. However, if desirable, the pins 4 and 5 could be made in one, and the lug 7 which 80 coacts with the pin 4 could be placed correspondingly near the small end of the head.

In use, one of the pins, as 5, is inserted in the bolt hole 11 of flange 10 and the corresponding lug as 6 is engaged on the outer periphery of the said flange. Then, by exerting pressure on the outer end of the handle in the direction of the arrow shown in Fig. 2, the flange may be turned on the pipe 12. 85 90

I am aware that heretofore wrenches for this purpose have been used which were provided with a lug designed to engage the periphery of the flange. With these devices, however, the lug is on the longitudinal median line of the wrench, consequently when pressure is applied, a twisting action is exerted on the pin which is inserted in the bolt-holes.

By making the head wide across the base 100 and positioning the engaging lug to one side of the longitudinal center line, I overcome this objection as it will be apparent from the fact that the lug 6 and lip 8 engaging the outer edge of the flange, exert a turning 105 movement about the longitudinal axis of the wrench which is opposite in character to the twisting action of the wrench itself. It will also be apparent that the wider the head is made across the lugs, the less will be the 110 twisting action on the pins.

Having thus described my invention, I

claim as new and wish to cover by Letters Patent:—

1. A flange wrench comprising a head having a face adapted to rest against the face of the flange, a handle in longitudinal alinement with said head, a pin extending outwardly from the face of said head adapted to engage openings in the flange, and a lug adapted to engage the peripheral edge 10 of the flange, said lug extending outwardly from the face of said head at one side of the longitudinal median line thereof.

2. A flange wrench comprising a head, a handle, a pin extending outwardly from one 15 of the faces of said head, a lug positioned laterally with respect to the longitudinal median line of said head and extending outwardly from the face thereof parallel to said pin, and an inwardly extending lip on the 20 outer end of said lug.

3. A flange wrench comprising a head having a face adapted to rest against the face of the flange, a handle in longitudinal alinement with said head, a pin projecting from 25 the face of said head, a lug projecting from the same face of said head parallel to said pin and having a face at an acute angle to the longitudinal median line of the wrench and tangential to a circle, the center of 30 which is in the axis of said pin, and a laterally extending lip on the outer end of said lug.

4. A flange wrench comprising a substan-

tially wedge-shaped head, a handle joining said head at the wide end thereof, a pin disposed in the longitudinal median line of said head and extending outwardly from the face thereof at the small end, a lug extending outwardly from the face of said head at the edge of the wide end thereof, and a lip 40 on the outer end of said lug.

5. A flange wrench comprising a head having a face adapted to rest against the face of the flange, a handle extending from said head, a pin projecting from the face of 45 said head at the opposite end from said handle, and a lug projecting from the same face of said head at one side of the median line thereof.

6. A flange wrench comprising a head, a 50 handle, a pin extending outwardly from one of the faces of said head, and a lug positioned laterally with respect to the longitudinal median line of said head and extending outwardly from the face thereof parallel to said pin.

7. A flange wrench comprising a substantially wedge-shaped head, a handle joining said head at the wide end thereof, a pin disposed in the longitudinal median line of said 60 head and extending outwardly from the face thereof at the small end, and a lug extending outwardly from the face of said head at the edge of the wide end thereof.

In testimony whereof I affix my signature. 65
JOSEPH G. ALLMON.
